UNITED STATES PATENT OFFICE

WILLIAM H. GREENLEAF, OF HARTFORD, CONNECTICUT, ASSIGNOR TO WESTERN CLOCK COMPANY, OF PERU, ILLINOIS, A CORPORATION OF ILLINOIS

POWER-CONTROLLING MECHANISM FOR TIMEPIECES

Application filed December 7, 1926. Serial No. 153,193.

My invention relates to that class of mechanism employed for maintaining an amount of power sufficient for the continuous and practicable operation of a time piece, and an object of my invention, among others, is the production of a mechanism of this type that shall be extremely simple in construction and particularly efficient in operation.

One form of mechanism embodying my invention and in the construction and use of which the objects herein set out, as well as others, may be attained, is illustrated in the accompanying drawings, in which—

Figure 1 is a view in elevation of a mechanism embodying my invention.

Figure 2 is a similar view looking from a point located at right angles to the point of view of Figure 1.

Figure 3 is a plan view with one of the supporting plates removed.

Figure 4 is an isometric view showing the parts unassembled and in relative positions for being assembled.

Figure 5 is an isometric view of the assembled structure.

As hereinbefore mentioned my invention is adapted for use in connection with time pieces, and especially of the type in which electrically operated means are employed for controlling the operation of the clock movement, the invention relating especially to such electrical mechanism or unit and the parts directly operated thereby, and for this reason only such parts as are necessary to an understanding of the invention are illustrated in the drawings herein. This electrical mechanism or unit embodying my invention is adapted for use in connection with various types of time pieces, such for instance as is shown in my United States Patent No. 1,525,179, dated February 3rd, 1925, and to which patent reference is hereby made for any further understanding that may be desired of such clock mechanism.

My improved magnet mechanism or unit includes in its construction two supporting plates 6—7 secured together as by tie posts 8 and between which plates said unit is located. The plate 6 is preferably composed of steel which is a magnetic metal and it therefore

acts as a baffle plate to absorb the magnetic flux and thereby prevent interference of such flux with the clock mechanism which is, in an approved type, closely associated with the electrical mechanism, the numeral 9 indicating one of the plates of the clock mechanism which may be secured to the plate 6 as by means of clips 10, it being understood that such clock mechanism may consist of two of such plates secured together in spaced relation and supporting the pinions, gears, &c., comprising the clock mechanism between them.

The magnet member hereinbefore referred to embodies a toe plate 11 of the usual non-magnetic material and a heel iron 12. This plate 11 and iron 12 are similar, in so far as shape is concerned, each of said pieces having on opposite edges tangs 13 adapted to fit and be secured, as by riveting or otherwise, within holes in the plates 6 and 7. The plate 11 may be secured to projecting ends 14 of the cores of the magnets in any suitable manner, as by riveting, it being observed that in the construction herein shown two coils 15 are used although this number of coils is not absolutely essential to the construction.

The projecting ends 16 of the cores opposite the ends 14 are polygonal in form in cross section and a filling piece 17 of insulating material is shaped to fit upon each of these ends 16 and against the end plate 18 of the coil. A terminal plate 19 is formed with an opening to fit one of the filling pieces and a terminal plate 20 is formed with an opening to fit the other of said filling pieces, each of these terminal plates being provided with a hole to receive an end 21 or 22 of one of the coils, which ends are secured to the plates in any suitable manner. Each of said plates 19—20 has a contact 23 or 24 extending therefrom, and an insulating plate 25 is formed with an opening to fit the filling piece 17 on each of the coils.

The terminal plate and insulating plate appurtenant to each filling piece 17 have a combined thickness equal to substantially that of the filling piece, so that the heel iron 12 will be seated squarely against the filling pieces and the insulating plates 25.

This is of special importance, as it aids in the simplicity of the construction. The plates 6 and 7 are provided, as hereinbefore stated, with openings for the tangs 13, said openings being spaced a certain distance apart on each plate. These plates are made up in quantities, as are the coils 15, the latter being all of substantially the same length, and by providing the filling pieces 17 of a definite thickness relative to the openings in the plates 6 and 7, the tangs 13 on the heel iron 12 will be spaced from the tangs on the toe plate 11 substantially the distance between the openings in the plates 6 and 7, in each assemblage of a coil unit, so that no difficulties will be encountered in attaching the coil units to the plates 6 and 7.

The heel iron is provided with openings 26 to fit the projecting ends 16 of the cores, and a slot 27 extends from one to the other of said openings. A positioning piece 28 of insulating material is secured in the slot 27 with its ends preferably in contact with the ends 16 of the cores. The ends 29—30 of the coils opposite the ends 21—22 extend through notches 31 in the terminal plates 19—20, through similar but smaller notches in the insulating plates 25 and into holes in the positioning piece 28, which holes are located to position the ends 29—30 so that they will not make contact with the plates 19 or 20. The ends 29—30 are then bent over and inserted in a hole 32 at about the lengthwise center of the positioning piece and these ends may be connected as by a piece of solder 33. The heel iron may be secured to the projecting ends of the core in any suitable manner, as by peening over the ends of the latter.

The end of the contact 23 is bent, as shown in Figure 2, to make direct contact with a terminal plate 34 of a binding post 35 that passes through the plate 7, and is suitably insulated therefrom, as shown in Figure 2 of the drawings, said post being connected with one pole of the battery. The contact 24 is positioned for engagement by a make-and-break lever 36 pivotally mounted on the plate 7, said lever being grounded on said plate and a binding post 37 to receive a connection from the opposite pole of said battery is also grounded on said plate. The make-and-break lever 36 operates and is operated in a manner set out in my hereinbefore referred to patent, this operation, however, not requiring a specific explanation for a complete understanding of the invention set forth herein.

In accordance with the provisions of the patent statutes I have described the principles of operation of my invention, together with the device which I now consider to represent the best embodiment thereof; but I desire to have it understood that the device shown is only illustrative and that the invention may be carried out by other means and

applied to uses other than those above set out.

I claim—

1. A power controlling mechanism including two main supporting plates spaced apart and each having openings spaced apart in position to register with the openings in the other plate, a power controlling element located between said main supporting plates and including a supporting member secured to each end of the power controlling element, tangs upon said members arranged to engage said openings, and means for spacing said plates on said controlling element to position said tangs to register with said openings. 70 75 80

2. A power controlling mechanism including two plates spaced apart and each having openings spaced apart in position to register with the openings in the other plate, a magnet located between said supporting plates and including a toe plate and a heel iron secured to the cores of the magnet, said toe plate and iron each having tangs upon opposite edges thereof to engage said openings, and means for spacing one of said parts secured to said magnet from the other of said parts to position said tangs to register with said openings. 85 90 95

3. A power controlled mechanism including two main supporting plates spaced apart and each having openings spaced apart in position to register with openings in the other plate, a power controlling element including a magnet, a supporting member secured to the core at each end of the magnet, and means mounted on a core of a magnet to space one of said supporting members from the other in position to register with said openings. 95 100 105

4. A power controlling mechanism including two supporting plates spaced apart and each having openings spaced apart in position to register with the openings in the other plate, a power controlling element located between said supporting plates and including a magnet comprising a core, a filling piece fitting a projecting end of said core, a heel iron secured to said core against said filling piece, a toe plate secured to the opposite end of said core, and tangs upon opposite edges of said heel iron and toe plate positioned to register with said openings. 110 115 120

5. A power controlling mechanism including two supporting plates spaced apart and each having openings spaced apart in position to register with the openings in the other plate, a power controlling element comprising a magnet consisting of two coils located between said supporting plates, a toe plate secured to the projecting ends of the cores of each of said coils at one end of the magnet, a filling piece secured to the projecting end of each core at the opposite end of the magnet, and a heel iron secured to the projecting ends of the cores and resting against 125 130 135

each of said filling pieces, said toe plate and heel iron having projections adapted to register with and be secured in said openings.

6. A power controlling mechanism including two supporting plates spaced apart, a power controlling element located between and secured to said plates, said element comprising a magnet, a terminal attached to the end of the core of said magnet and having a contact, a terminal on one of said supporting plates, and means for securing said magnet to said supporting plates in position to press said contact against said terminal.

7. A magnet including a coil and a core projecting beyond the end of the coil, a terminal plate secured at the end of said coil and insulated from said core, said plate having a hole to receive one end of the wire of said coil and a notch through which the other end of said coil passes, and a member secured to the end of said core and having means to position said other end of said wire to prevent its contact with the edges of said notch.

8. A magnet including a coil and a core projecting beyond the end of the coil, a terminal plate secured at the end of said coil and insulated from said core, said plate having a hole to receive one end of the wire of said coil and a notch through which the other end of said wire passes, a positioning piece secured to the end of said core and having means to receive said wire and position it to maintain it out of contact with the edges of said notch, and a heel iron secured to said core and having means to receive said other end of said wire.

9. A magnet including a coil and a core having a reduced end projecting beyond the end of the coil, a filling piece secured to said reduced end of the core, a terminal plate having an opening to fit over said filling piece, a hole to receive one end of the wire comprising the coil and a notch through which the opposite end of said wire passes, an insulating plate fitting over said filling piece and having means to position said other end of the wire to prevent contact with the edges of said notch, and means secured to said core to receive said other end of said wire.

10. A magnet including a coil and a core having a reduced end projecting beyond the end of the coil, a filling piece secured to said reduced end of the core, a terminal plate fitting over said filling piece and having a hole to receive one end of the wire comprising the coil and a notch in said opening through which the other end of said wire passes, an insulating plate fitting over said filling piece and having a positioning notch in the edge of its opening to receive said other end of said wire and maintain it out of contact with the edges of said notch, and means secured to the end of said core to hold said terminal

plate and insulating plate in place and provided with means for attachment of said other end of said wire.

11. A magnet including a plurality of coils and a core projecting at the end of each coil, and conducting plates secured to one end of the wire comprising each of said coils, a plate secured to the projecting ends of said cores, and an insulating piece secured to said plate and having means to receive and hold the opposite ends of the wires comprising each of said coils.

12. A magnet including a plurality of coils and a core projecting at the end of each coil, conducting plates secured to one end of the wire comprising each of said coils, a plate secured to the projecting ends of said cores and having a slot therein, and an insulating piece secured within said slot and having means to receive and hold the opposite ends of the wires comprising each of said coils.

13. A magnet including a plurality of coils and a core projecting at the end of each coil, conducting plates secured to one end of the wire comprising each of said coils, a plate secured to the projecting ends of said cores, and an insulating piece secured to said plate and having end holes for the reception of the opposite ends of said wires and an intermediate hole to receive the opposite ends of both of said wires.

14. A magnet including a plurality of coils and a core projecting at the end of each coil, conducting plates each secured to one end of the wire comprising each of said coils, and supported by the ends of said cores, said conducting plates each having an opening through which a wire passes, a heel iron secured to the projecting ends of said cores, and a positioning piece of insulating material secured to said heel iron and having an end opening for one end of a wire comprising each of said coils and a center opening for the opposite ends of said wires.

15. A magnet including a plurality of coils and a core projecting at the end of each coil, conducting plates supported by the ends of said cores and each having means of attachment of one end of a wire comprising each of said coils, said conducting plates also having openings through which one end of each of said coils passes, a heel iron secured to the projecting ends of said cores and having a slot therein, a positioning piece of insulating material secured within said slot and having an opening at opposite ends to receive one end of a wire comprising one of said coils and a center opening to receive both ends of said wires, and means for securing the ends of said wires together within said center opening.

16. The combination with a magnet including field cores, a yoke connecting said cores, and coils mounted on said cores, of means interposed between the yoke and the coils for supporting the leads of said coils.

17. The combination with a magnet including field cores, a yoke connecting said cores, and coils mounted on said cores, of means mounted on the cores between the coils and the yoke for supporting the leads of said coils. 70
18. The combination with a magnet including field cores, a yoke connecting said cores, and coils mounted on said cores, of means interposed between the yoke and the coils for providing terminals for the coils. 75
19. The combination with a magnet including field cores, a yoke connecting said cores, and coils mounted on said cores, of means mounted on the cores between the coils and the yoke for providing terminals for the coils. 80
20. The combination with a magnet including field cores, a yoke connecting said cores, and coils mounted on said cores, of means mounted on the cores between the coils and the yoke and insulated from the cores and the yoke for providing terminals for the coils. 85
21. The combination with a magnet including field cores, a yoke connecting said cores, and coils mounted on said cores, of means interposed between the yoke and the coils for providing terminals for one lead of each coil, and means for insulating said last mentioned means and also the remaining leads of said coils from the cores and the yoke. 90
22. The combination with a magnet including field cores, a yoke connecting said cores, and coils mounted on said cores, of means secured to the yoke and supporting one lead from each coil to permit said leads to be attached so as to interconnect the coils. 95
23. In combination, a magnet including a slotted yoke, and means secured in the slot for supporting coil leads. 100
24. In combination, a magnet including a slotted yoke, and an insulating member positioned in said slot and apertured to receive coil leads. 105
25. In combination, a magnet including a yoke having openings to receive the ends of field cores and having a slot located between said openings, of means positioned in said slot for supporting coil leads. 110
26. In combination, a magnet including a yoke having openings to receive the ends of field cores and having a slot communicating with said openings, and an insulating member filling said slot for supporting coil leads. 115
27. In a device of the type described, a pair of supporting plates, a plurality of magnet cores, and means for connecting the cores in proper spaced relation with respect to each other and for connecting the cores to said plates. 120
28. In a device of the type described, a pair of supporting plates, a plurality of magnet cores having their axes extending in parallelism with the planes of said plates, and 125
